[57] **CLAIM**

The ornamental design for a storage and dispensing apparatus for spooled materials, as shown and described.

DESCRIPTION

FIG. 1 is a front elevational view of a storage and dispensing apparatus for spooled materials showing our new design therefor. The spool-holding portion of the apparatus is shown removed to better illustrate its design features; the broken line drawing representing a spool is for purposes of illustration only and forms no part of our design;

FIG. 2 is a front elevational view;

FIG. 3 is a rear elevational view;

FIG. 4 is a right side elevational view;

FIG. 5 is a left side elevational view;

FIG. 6 is a top plan view; and,

FIG. 7 is a bottom plan view.
